UNITED STATES PATENT OFFICE.

JULIUS PETERSON, OF MOLINE, ILLINOIS, ASSIGNOR TO DEERE & COMPANY, OF MOLINE ILLINOIS, A CORPORATION OF ILLINOIS.

LISTER PLOW.

Application filed January 5, 1927. Serial No. 159,030.

My invention relates to lister plows, and more particularly to the means employed to secure the plow body to the plow beam, said means comprising a frog made of sheet metal 5 and formed to such a shape best suited to be rigidly secured to the plow and the plow beam.

Referring to the drawing in which similar numerals indicate identical parts:

10 Figure 1 is a bottom plan view of a lister plow and its beam and my improved frog thereon.

The plow body consists of the share 1 and the moldboards 2 and 3, the latter secured 15 to the share 1 by straps 4 and 5 bolted to the share and the moldboards 2 and 3 respectively. The frog 4^a is bent on an approximately central longitudinal line 5^a; one side 6 of the frog is rigidly attached to 20 the share by bolts 7 and to one of the moldboards by bolts 8, and fits snugly to the moldboard 2. The opposite side 9 of the frog, for part of its length forwardly, fits snugly to the share 1 and the moldboard 3, and is secured 25 rigidly to the share 1 by bolt 7 and to the moldboard 3 by a bolt 10.

Rearwardly of the bolt 10, the part 9 of the frog is bent rearwardly and inwardly, as at 11, to form a loop having a flattened 30 portion 12 adapted to contact with a side of the plow beam 13 at which point it is secured to the beam by a bolt 14. Rearwardly of the bolt 14, the part 9 is bent to form a reverse loop having a flattened 35 portion 15, which is attached to the moldboard 3 by a bolt 16. The rear loop terminates in a rearwardly extending part 17 bent in parallelism with the beam 13 to which it is rigidly secured by a bolt 18. Forwardly 40 the frog terminates in a point 19.

It is well known in the art and manufac-

tures that frogs, utilized in lister plows, are made of cast iron, fitting snugly to the plow parts and having a central longitudinal web to which the plow beam is attached. The 45 cast frog, however, has undesirable features which I have eliminated by making the frog of sheet steel, and upsetting or bending one side of the frog not only to secure it properly to a plow beam, but to dispense with the 50 central web of the cast frog as generally used to secure the beam and frog together. By bending one side of the frog in the manner shown and described, the danger of 55 breakage, common in cast frogs from lateral strain, has been removed, the effective and durable qualities of the frog have been materially increased and the cost of manufacture materially lessened. As a new article of manufacture, the frog can be readily supplied in quantity to meet the demand for a 60 stronger and more durable frog than is commonly in use.

What I claim is:

As a new article of manufacture, a frog 65 for lister plows made of sheet metal bent at its longitudinal center and having a forward pointed termination; said frog on one side of said center, for its entire length, adapted to conform to the underside of a lister plow 70 body; and similarly formed forwardly, for part of its length, on the opposite side of said center; a loop upset rearward of said part having a flattened portion for attachment to a plow beam; a reverse loop adjacent said first mentioned loop, with its central part adapted to be attached to a lister plow body; said reverse loop having a rearwardly extended part adapted to be secured 75 to a lister plow beam. 80

JULIUS PETERSON.
